UNITED STATES PATENT OFFICE

118,574

DESIGN FOR A COMBINATION CONTAINER PACKAGE

Albert W. Stompe, Neenah, Wis., assignor to Marathon Paper Mills Company, Rothschild, Wis., a corporation of Wisconsin

Application May 23, 1939, Serial No. 85,167

Term of patent 14 years

To all whom it may concern:

Be it known that Albert W. Stompe, a citizen of the United States, residing at Neenah, Winnebago County, in the State of Wisconsin, has invented a new, original, and ornamental Design for a Combination Container Package, of which the following is a specification, reference being had to the accompanying drawing forming a part thereof.

Figure 1 is a perspective view of a combination container package, showing my new design; and Figure 2 is an end view.

I claim:

The ornamental design for a combination container package, as shown.

ALBERT W. STOMPE,
